Attest.

UNITED STATES PATENT OFFICE.

LEON GEDGAUD, OF CHICAGO, ILLINOIS.

DESIGN FOR A LAMP-POST.

Application filed February 23, 1928. Serial No. 25,548. Term of patent 3½ years.

To all whom it may concern:

Be it known that I, LEON GEDGAUD, a citizen of the United States of America, residing at Chicago, in the county of Cook and State of Illinois, have invented a new, original, and ornamental Design for a Lamp Post, of which the following is a specification, reference being had to the accompanying drawing, forming part thereof.

The figure is a perspective elevational view showing my design.

I claim:

The ornamental design for a lamp post, as shown.

LEON GEDGAUD.
